Primary Examiner — Gino Colan(74) *Attorney, Agent, or Firm* — Christopher A. Proskey; BrownWinick Law Firm(57) **CLAIM**

The ornamental design for a track horse, as shown and described.

DESCRIPTION

FIG. 1 is a side elevation of a track horse showing my new design,

FIG. 2 is an end elevation view thereof;

FIG. 3 is a top plan view thereof;

FIG. 4 is a bottom plan view thereof;

FIG. 5 is a side elevation view thereof, shown in a retracted position;

FIG. 6 is a bottom plan view thereof, shown in a retracted position;

FIG. 7 is a top perspective view thereof;

FIG. 8 is another top perspective view thereof;

FIG. 9 is a bottom perspective view thereof; and,

FIG. 10 is another top perspective view thereof.

The broken lines shown in the figures are for the purpose of illustrating environment and form no part of the claimed design.

1 Claim, 10 Drawing Sheets# US D925,065 S
